UNITED STATES PATENT OFFICE.

CHARLES BOGENSCHUTZ, OF COVINGTON, KENTUCKY.

DESIGN FOR A RANGE OR STOVE.

SPECIFICATION forming part of Design No. 32,668, dated May 15, 1900.

Application filed October 1, 1897. Serial No. 653,753. Term of patent 7 years.

To all whom it may concern:

Be it known that I, CHARLES BOGENSCHUTZ, a citizen of the United States, residing at Covington, Kenton county, State of Kentucky, have invented and produced a new and original Design for Ranges and Stoves; and I hereby declare the following to be a clear, full, and exact description thereof and such as will enable others skilled in the art to which it applies to make and use the same, reference being had to the accompanying drawing, which shows a perspective view of a range provided with my design.

The object of the design is to impart to a range certain configurations, as shown, and serving for ornamental purposes. They consist, substantially, of heart-shaped shields A,

provided in suitable positions—as at the doors D, base, or top, for instance—which shields are surrounded by suitable ornamentations, the whole appearing in relief. The field within such shields may afford the necessary space to accommodate the name of the manufacturing firm or its trade-mark. The same ornamentations are repeated on the sides wherever the design is used thereat.

Having described my design, I claim the same as follows:

The design for a range or stove, substantially as herein shown and described.

CHARLES BOGENSCHUTZ.
